UNITED STATES PATENT OFFICE.

ALFRED KREMER, OF MOUNT PLEASANT, PENNSYLVANIA, ASSIGNOR OF ONE-HALF TO
LEO P. KELLER, OF MOUNT PLEASANT, PENNSYLVANIA.

AEROPLANE.

1,266,490.

Specification of Letters Patent. Patented May 14, 1918.

Application filed September 11, 1917. Serial No. 190,799.

To all whom it may concern:

Be it known that I, ALFRED KREMER, a subject of the Emperor of Germany, have taken out first papers to become a citizen 5 of the United States of America, residing at Mount Pleasant, in the county of Westmoreland and State of Pennsylvania, have invented certain new and useful Improvements in Aeroplanes, of which the following 10 is a specification.

My invention relates to improvements in aeroplanes.

The primary object of the invention is to provide in an aeroplane, a top plane, a 15 part of which is formed by two side sub-planes, which with said plane form a flat surface, but which may be tilted to maintain the aeroplane in the proper controlled position.

20 A further object of the invention is to provide a pair of sub-planes which normally form part of a top plane, held in normal flat position by springs, means being provided for tilting one sub-plane against the 25 tension of the springs, and simultaneously freeing the opposite sub-plane to permit the air to tilt the latter sub-plane upwardly to balance the machine when in flight.

A further object of the invention is to 30 provide means for separately controlling the sub-planes to balance the machine in flight, and to provide means for simultaneously tilting said sub-planes to form a greater air resisting surface to steady the 35 machine when making a landing or when coasting.

The invention also comprehends improvements in the details of construction and arrangement of parts which will be herein- 40 after described and particularly pointed out in the claims.

In the accompanying drawings:

Figure 1 is a perspective view of my improved aeroplane, the motor and many of 45 the ordinary operating appliances, and the usual braces being omitted,

Fig. 2 is a top plan view,

Fig. 3 is a side elevation showing one of the sub-planes tilted upwardly under the influence of the air,

Fig. 4 is a front elevation, showing the sub-planes tilted,

Fig. 5 is a detail cross section of the hinge connection between the sub-plane and 55 the top frame,

Fig. 6 is a similar view showing the spring connection,

Fig. 7 is a detail view of the control lever.

1 indicates a frame; 2, the upper member thereof; and 3, the lower member.

The lower member 3, is substantially T-shape in plan view, and is provided with a forward plane and platform 4, and a rear elongated plane 5. The upper member 60 2, is substantially T-shape in plan view, and is provided with a flat plane 6. The side edges 7-7 of the rear portion of the upper plane 6, flare outwardly and rearwardly, to provide a widened surface at the 70 extreme rear, for a purpose to be described. Hinged to the edges 7-7 of the frame member are flat side sub-planes 8-8, the outer edges of said sub-planes inclining rearwardly and inwardly toward a medial line 75 drawn through the center of the upper plane. The forward wide ends of the sub-side-planes fit behind the transverse front portion of the upper plane, while the narrow rear ends terminate substantially in a 80 plane with the rear widened edge of the reduced portion of the plane 6.

Springs 9, are arranged between the matching edges 7, of the plane 6, and the corresponding edges of the sub-planes, to 85 normally hold the sub-planes in a horizontal plane with the upper plane 6.

It follows from the construction thus far described that the upper plane 6, and the side sub-planes normally present a flat surface, the edges of which taper rearwardly.

10 indicates a standard rising from the platform, and at its upper end it is provided with a socket bearing 11. Mounted in the socket bearing is a ball 12, and depending 95 therefrom is a lever 13. Mounted on a pin (not shown), extending from the lever 13, is a drum 16, having a hand wheel 17. Cables 20, are oppositely wound around the drum, and extend in opposite directions. 100 These cables pass over guide pulleys 21, and up to the forward outer corners of the side sub-planes. From the cables 20, above the guide pulleys 21, extend branch cables 22, which are attached to the rear outer corners of the sub-planes, to equalize the pull 105 on the sub-planes when tilted against the tension of the springs.

To the lower end of the lever 13, are secured the ends of two cables 23, which pass 110

guides, and are attached at their opposite ends to the cables 20. The normal position of the lever 13, is inclined as shown in Fig. 1, at which time the two branch cables 23, 5 are slack to permit of the cables 20, tilting but one of the sub-planes when the drum is rotated. If it be desired to tilt both sub-planes downwardly, as shown in Fig. 4 the drum is rotated to restore the planes to their 10 normally horizontal position, in which position they are maintained by the springs. Then the lever 13 is titled forwardly to neutral position which takes up the slack in the cables 23, and upon further movement pull 15 is exerted on said cables which likewise pulls on the cables 20, and the two sub-planes are tilted downwardly.

Extending from the front of the machine is a frame 25, and mounted in its forward end 20 is a horizontal rudder 26, and projecting from the journals thereof are upper and lower arms 27. From the upper arms extend cables 28, which pass over guides 29, and are attached to a lever 30, pivoted to the platform. Extending from the lower arms 27, are similar 25 cables 31, which extend over guides 32, and are attached at their ends to the lever 30, below the pivot thereof. Obviously by operating the lever 30 the horizontal rudder is 30 tilted to steer the machine either up or down, as desired.

At the rear of the machine is a pivoted vertical rudder 35, and projecting from the rear thereof are extensions 36, and attached 35 to the extensions are cables 37, the forward ends of which are attached to a foot lever 38, pivoted on the platform.

The exact position of the control levers, and the specific construction employed are 40 not shown in the drawings as it is deemed sufficient to illustrate the features conventionally, and it is evident that the location of the levers can be at such points as may be found most convenient.

45 As previously outlined the fundamental features of this invention reside in the construction and arrangement of the flat sub-planes and means for operating them.

When flying, if it be desired to steady the 50 machine in rounding a curve, or if a sudden air current should strike one side of the upper plane, and it is necessary to offer greater air resistance on one side to retain the place of the machine under control, the drum 16 55 is rotated, and one sub-plane is tilted downwardly, somewhat like a bird's wing, while the cable connected to the opposite sub-plane is slackened. Immediately this cable is 60 slack, the air current acting on the under side of the sub-plane is tilted upwardly against the tension of the springs, which promptly reduces the air resistance on that side. In this connection it is to be noted that the air current acts to raise the sub- 65 plane to reduce the resistance, while the op-

posite sub-plane is manipulated by the operator.

By this means the machine is under perfect control of the operator, as the positive movement of but one sub-plane acts to limit 70 the movement of the companion sub-plane under the influence of the air current. Of course the tilting or manipulating of the sub-plane is for the purpose of steadyng or 75 balancing the machine while in flight, and under ordinary circumstances the sub-planes are maintained in horizontal position to present with the top plane 6, a flat horizontal surface.

If in descending, or for any other reason 80 it be desired to tilt both sub-planes downwardly simultaneously to offer a greater resistance to the air, the drum must first be returned to normal position to position the sub-planes in a plane with the plane 6. Then the lever 13 is moved forwardly, to approximately a vertical position to take up the slack in the cables 23. Upon further forward movement of the lever 13, pull is exerted on the now taut cables, and the sub-planes are tilted downwardly on their 85 hinges, in which position they afford a greater resistance to the air, and therefore retard the speed of the machine downwardly. From the foregoing description it 90 is evident that the sub-planes not only act to retain the machine in balance when rounding a curve or when encountering a sudden air current, but in addition to this function the planes can be manipulated to afford a 95 greater resistance than when necessary for ordinary flying, to facilitate descent or making a landing.

Of course the vertical and horizontal rudders are employed and used in the same manner as in ordinary aeroplanes, for which reason it is not deemed necessary to describe their operation. They are but conventionally shown, as they must necessarily be employed in connection with my improved 105 sub-planes.

By flaring the upper and lower main planes to provide greater air resistance surface at the rear of the machine, it follows that when the sub-planes are tilted the air is 110 trapped with the result that increased resistance is provided, and a more ready and convenient means for steadyng the machine is produced.

What I claim is:—

120 1. An aeroplane comprising, a transverse sustaining plane, a longitudinal sustaining plane arranged rearwardly of the transverse plane and disposed in the plane thereof, sub-planes arranged upon the opposite 125 sides of the longitudinal plane in the rear of the transverse plane and adapted to be arranged in the plane of the transverse plane, means pivotally connecting the longitudinal edges of the sub-planes with the 130

longitudinal edges of the longitudinal plane so that said sub-planes are adapted to be swung transversely of the longitudinal plane, a pivoted lever, a drum pivotally connected with the lever, a cable connected with the sub-planes and wound upon the drum to alternately swing the sub-planes downwardly, and means connecting the lever with the cable for simultaneously swinging the sub-planes downwardly.

2. An aeroplane comprising, a transverse sustaining plane, a longitudinal sustaining plane disposed rearwardly of the transverse plane and having rearwardly diverging longitudinal edges, substantially triangular sub-planes arranged outwardly of and near the rearwardly diverging longitudinal edges of the longitudinal plane, said sub-planes decreasing in width rearwardly, means pivotally connecting the longitudinal edges of the sub-planes with the longitudinal edges of the longitudinal plane so that the sub-planes are adapted to be swung transversely of the longitudinal plane, a pivoted lever, a drum pivotally connected with the lever, a cable connected with the sub-planes and wound upon the drum to alternately swing the sub-planes downwardly, and means connecting the lever with the cable for simultaneously swinging the sub-planes downwardly.

3. An aeroplane comprising, a transverse sustaining plane, a longitudinal sustaining plane arranged rearwardly of the transverse plane, sub-planes arranged upon the opposite sides of the longitudinal sustaining plane and pivotally connected therewith to be swung transversely thereof, a pivoted lever, a drum pivotally connected with the lever, a cable connected with the sub-planes and wound upon the drum to alternately swing each sub-plane downwardly, and means whereby the sub-planes may be simultaneously swung downwardly by the movement of the pivoted lever.

4. An aeroplane comprising, a transverse sustaining plane, a longitudinal sustaining plane arranged rearwardly of the transverse plane, sub-planes arranged upon opposite sides of the longitudinal sustaining plane and pivotally connected therewith to be swung transversely thereof, a standard, a

lever provided near its upper end with a universal connection with the standard, a drum pivotally connected with the lever near its upper end, a hand-wheel connected with the drum, a cable connected with the sub-planes and wound upon the drum to alternately swing each sub-plane downwardly, and means connecting the lower portion of the lever with said cable so that said lever may serve to simultaneously swing the sub-planes downwardly.

5. An aeroplane comprising, a transverse sustaining plane, a longitudinal sustaining plane disposed rearwardly of the transverse plane and having rearwardly diverging longitudinal edges, sub-planes hinged to the rearwardly diverging longitudinal edges of the longitudinal plane and longitudinally tapered and decreasing in width rearwardly, said sub-planes having outer longitudinal edges which converge rearwardly with respect to the longitudinal axis of the longitudinal plane when the sub-planes are in the normal upper position, the forward portions of the sub-planes serving to pocket the air, which discharges from the rearwardly converging edges thereof in increasing velocity rearwardly, when the sub-planes are lowered, and means to swing the sub-planes to the lowered position.

6. An aeroplane comprising, a transverse sustaining plane, a longitudinal sustaining plane disposed rearwardly of the transverse plane, sub-planes hinged to the longitudinal edges of the longitudinal plane and adapted to assume upper positions in the plane thereof, said sub-planes being longitudinally tapered and decreasing in width rearwardly and having outer longitudinal edges which converge rearwardly with respect to the longitudinal axis of the longitudinal plane when the sub-planes are in the upper position, the forward portions of the sub-planes serving to pocket the air, which discharges from the rearwardly converging longitudinal edges thereof in increasing velocity rearwardly, when the sub-planes are lowered, and means to swing the sub-planes to the lowered position.

In testimony whereof I affix my signature.

ALFRED KREMER.
